UNITED STATES PATENT OFFICE.

CHARLES F. SMITH, OF BROOKLYN, NEW YORK.

PERISCOPIC FIELD-GLASS.

1,178,545.

Specification of Letters Patent. Patented Apr. 11, 1916.

Application filed October 12, 1915. Serial No. 55,481.

To all whom it may concern:

Be it known that I, CHARLES F. SMITH, a citizen of the United States, residing at Brooklyn, in the county of Kings, State 5 of New York, have invented certain new and useful Improvements in Periscopic Field-Glasses; and I do hereby declare the following to be a full, clear, and exact description of the invention, such as 10 will enable others skilled in the art to which it appertains to make and use the same.

The present invention is directed to improvements in periscopic field glasses, and has for its object to so construct a device 15 of this character that the same can be folded in a compact form when not in use, and readily extended for use.

A further object of the invention is to provide a device of this character so constructed that the same can be folded into 20 compact form and inclosed in a casing supported by a conventional form of field glass.

With these and other objects in view, this invention resides in the novel features of 25 construction, formation, combination and arrangement of parts to be hereinafter more fully described, claimed and illustrated in the accompanying drawing, in which:

Figure 1 is a side elevation of the device 30 showing the periscope extended. Fig. 2 is a front elevation of the same. Fig. 3 is a longitudinal sectional view through the device, showing the same folded. Fig. 4 is a sectional view on line 4—4 of Fig. 1. Fig. 35 5 is a similar view on line 5—5 of Fig. 1. Fig. 6 is a sectional view on line 6—6 of Fig. 1. Fig. 7 is a fragmentary view of the lower end of one of the bars of the side frames. Fig. 8 is a front elevation, showing 40 the device folded.

Referring to the drawing 1 indicates a conventional form of field glass, which has mounted thereon a casing 2, and associated with the open end of the casing is a hingedly 45 connected door 3. Slidable in the casing 2 is a frame 4, said frame having studs 5 carried thereby, and adapted to engage the upwardly projecting end 6 of the track 7, which is mounted in the casing 2, thereby 50 limiting the outward sliding movement of the frame. Lazy-tong side frames 8 are provided, and have their lower ends formed with slots 9, which are adapted to slidably engage the studs 10 carried by the sides of 55 the frame 4. Opening into the slots 9 are lateral slots 11. Thus it will be seen that

when the studs 10 are engaged in the slots 11, that the side frames 8 will be held in their extended positions, thereby holding the collapsible tube 12 in its extended position, 60 since the upper ends of the frames 8 are connected to the upper end of said tube. The frame 4 has its sides provided with grooves 4', which are adapted to slidably engage the tongue 7' of the track 7, thereby preventing tilting of the tube 12 when in its extended position. Hingedly connected with the upper end of the tube 12 is the back plate 13 of the reflecting mirror 14, while hingedly connected to the upper end of said 70 plate is a top plate 15, which has its forward end provided with spring clips 16, the same being adapted to engage the upper bar of the rectangular frame 17, which has its bottom bar hingedly connected to the top 75 of the tube 12. Hingedly connected to the lower end of the tube 12 is a plate 18, which supports the mirror 19, said mirror being held in inclined relation to the lens of the glass 1 by pivotally connected links 20. The 80 sides of the plate 18 and lower end of the tube 12 are connected by flexible aprons 21.

When it is desired to use the periscope, it is only necessary to move the frame 4 from the casing 2 and extend the side frames 8, 85 after which the mirror 14 and mirror 19 are aligned so that the object viewed will be reflected from the mirror 14 to the mirror 19, so that a person using the field glass can make the proper observation. To fold the 90 periscope it is only necessary to disconnect the plate 15 from the frame 17, whereupon the mirror can be folded, as shown in Fig. 3 of the drawing. To prevent scratching of the mirror 14, one face of the top plate 15 95 has secured thereto a sheet of felt or the like. After the mirror 14 has been properly folded, the side frames 8 are collapsed, and therewith the tube 12, and rest upon the frame 4, which is moved inwardly to conceal the periscope within the casing 2, it 100 being of course understood that the mirror 19 has been folded.

The bottom of the casing 2 has attached thereto a cup-shaped plate 22, which has 105 formed therein a key hole slot 23 for receiving the head 24 of the clamping bolt 25, said bolt having its lower end connected to the cross bar 26 which engages the chambers of the field glass, as best shown in Fig. 110 8. Thus it will be seen that the casing can be quickly removed from the field glass,

when desired. The mirror 14 is also shaded by a suitable curtain 27, which may be secured in any suitable manner to the adjacent parts.

5. What is claimed is:—

1. A periscope attachment for field glasses comprising a casing adapted to be attached to the field glass, said periscope comprising a collapsible tube having mirrors hingedly associated with its upper and lower ends, said tube when folded being adapted to slide into the casing.
2. A periscope attachment for field glasses comprising a casing adapted to be attached to the field glass, a frame slidably associated with the casing, a collapsible periscope tube having reflecting mirrors hingedly associated with its upper and lower ends, and adapted to slide into the casing when the tube is collapsed.
3. A periscope attachment for field glasses comprising a casing adapted to be secured

to the field glass, a frame slidably engaged in the casing, a collapsible periscope tube having its lower end supported by the frame, collapsible side frames for holding the tube in its extended position, mirrors hingedly associated with the upper and lower ends of the tube, said mirrors being adapted to fold when the tube is collapsed and slide into the casing with the frame.

4. A periscope attachment for field glasses comprising a casing adapted to be detachably connected to the field glass, said periscope comprising a collapsible tube which when folded is adapted to slide into the casing.

In testimony whereof, I affix my signature in the presence of two witnesses.

CHARLES F. SMITH.
